BUILDING UNIT

Angle W. Powell, Boerne, Tex.

Application December 7, 1938, Serial No. 244,477

8 Claims. (Cl. 72—40)

My invention relates to building structures, and has among its objects and advantages the provision of improved steel-barred construction blocks.

An object of my invention is to provide a building block of such construction as to facilitate assembly of the blocks in a wall structure in which novel means are provided for effectively keying the blocks.

A further object is to provide a building block construction so designed as to permit quick and easy erection of the wall structure in which novel means are provided for keying the blocks into a unitary structure in such manner as to eliminate necessity for a bonding medium, extra reinforcing rods, metallic guides, bolts and the like.

Another object is to provide building blocks which may be formed of originally plastic material in which novel key means in the nature of rods are incorporated and so arranged as to provide vertical load-supporting reinforcement extending the full height of the wall.

In the accompanying drawings:

Figure 1 is a fragmentary view of a wall constructed of my blocks with certain parts illustrated in section for the sake of clearness;

Figure 2 is a sectional view along the line 2—2 of Figure 1;

Figure 3 is a sectional view along the line 3—3 of Figure 1;

Figure 4 is a perspective view of one of the lowermost foundation blocks;

Figure 5 is a perspective view of one of the second course foundation blocks;

Figure 6 is a perspective view of one of the wall blocks;

Figure 7 is a perspective view of a similar wall block;

Figure 8 is an elevational view of one of the wall blocks provided with ventilating openings;

Figure 9 is a similar view of one of the wall blocks provided with one ventilating opening;

Figure 10 is a perspective view of one of the eave plates;

Figure 11 is a transverse sectional view of the plate illustrated in Figure 10;

Figure 12 is a bottom plan view of the plate illustrated in Figure 10; and

Figure 13 is a plan view of a fragmentary wall structure illustrating the manner in which corner blocks are associated with the wall blocks to provide a building corner.

In the embodiment selected to illustrate my invention, Figure 1 illustrates the lowermost course 10 of the foundation building blocks 12 and the second course 14 of the foundation blocks

16. Upon the course 14 I mount a plurality of courses 18 of building blocks 20.

Figure 4 illustrates one of the foundation blocks 12. The block 12 has anchored therein three steel bars 22, 24 and 26. These three bars extend longitudinally of the block 12 and lie horizontally when the block is incorporated in the wall structure. Midway between the two bars 24 and 26 I provide a horizontal bore 28.

Bar 22 is positioned midway between two horizontal bores 30 which also extend longitudinally of the block. Bar 22 and the bores 30 lie in a common plane spaced from the bottom face 32 of the block the same distance that the plane of the bars 24 and 26 and the bore 28 lies below the top face 34. Both ends of the bars 22, 24 and 26 extend beyond the end faces 36 of the block equal distances, each of which distances equals half the length of the block.

Bars 24 and 26 are arranged in parallel relation with the bore 28, and the spacing between the bar 24 and the bore 28 corresponds exactly to the spacing between the bore 28 and the bar 26. Similarly, the spacing between one bore 30 and the bar 22 corresponds exactly to the spacing between that bar 22 and the other bore 30. Bar 24 is located vertically above the associated opening 30, while the bore 28 is vertically aligned with the bar 22. Similarly, the bar 26 is aligned vertically with the other bore 30. The bars are incorporated in the block at the time of manufacture so as to be effectively anchored therein.

In the course 10, the blocks 12 are positioned with their faces 36 in abutting relation. The projecting ends of the bars 22, 24 and 26 will extend into corresponding bores in the adjacent block 12 half its length. The adjacent block will differ in construction only in that the bar 22 of Figure 4 will be anchored in the position of the bore 28, while the bars 24 and 26 will be positioned in the location of the bores 30. Bore 28 will take the position of the bar 22, while the bores 30 will take the positions of the bars 24 and 26. Thus the blocks 12 may be assembled in end to end relation with the reinforcing and keying bars so arranged as to provide six continuous reinforcing elements extending the full length of the foundation course 10.

Referring again to Figure 4, the ends of two bars 38 are anchored in the block 12 and are positioned at right angles to the face 40, in addition to being disposed in a plane paralleling the side face 42. Between the bars 38 I provide a bore 44 which extends inwardly of the block about two-thirds its thickness. Bore 44 is positioned

exactly half way between the two bars 38. A second bore 46 also extends through the block about two-thirds its thickness. One of the bars 38 is positioned exactly half-way between the bores 44 and 46, while these bores and the bars 38 are positioned in a common plane. The block is also provided with two bars 48 and two bores 50, which bars and bores are relatively positioned in the same manner as the rods 38 and the bores 44 and 46, but are spaced from the side face 52 a greater distance than the spacing between the bars 38 and the bores 44 and 46 and their respective side face 42.

Figure 5 illustrates one of the foundation blocks 16 in the course 14. Blocks 16 are of the same height as the blocks 20, but all the blocks illustrated in Figure 1 are of the same length, with the blocks 16 equally overlapping two of the blocks 12. Foundation blocks 16 have a thickness approximately half that of the blocks 12, as illustrated in Figure 2. According to Figure 5, the block 16 is provided with two bars 54 having their ends extending beyond the faces 56 and 58 distances equal to half the height of the block. The block is also provided with two bars 60 of the same length as the bars 54. Bars 54 lie in a common plane with two bores 62, while the bars 60 are positioned in a common plane with two bores 64. Bars 54 and the bores 62 lie in a plane paralleling the face 66, while the bars 60 and the bores 64 lie in a plane paralleling the face 68, but at a greater distance from the face. When the blocks 16 are placed in position on the blocks 12, one bar 38 and one bar 48 associated with one of the blocks 12 will enter one opening or bore 62 and one bore 64 in the superposed block 16. At the same time, one bar 54 and one of the bars 60 will enter one opening 46 and one of the openings 40, 50 so as to key the two blocks. The adjacent block 12 underneath the superposed block 16 will be connected with the latter in the same manner. Thus one block 16 effectively keys two blocks 12 in connected relation.

Referring to Figure 6, the block 20 is provided with two vertical bores 70 and two vertical bars 72. Bores 70 are spaced to receive the two bars 54 of the block 16 underneath the same, while the lower ends of the bars 72 are arranged to pass into the bores 62. The lower ends of the bars 72 will abut the bars 38 associated with one of the foundation blocks 12, as illustrated in Figure 1. Face 58 of the block 16 is provided with a pair of ribs 74, and the lower end of the block 20 is provided with a groove 76 for receiving one of the ribs 74, with the face 76 of the block 20 lying flush with the outer wall face of the foundation block 16.

Referring to Figure 2, the blocks 20 are assembled to provide an outer wall shell 80 and an inner wall shell 82 spaced to provide an air space 84. The blocks 20 in the lower course 20 of the wall shell 82 are arranged so that the other ribs 74 on the building blocks 16 lie in the aligned grooves 78 in the blocks 20. The interfitting relation between the ribs 74 and the grooves 78 provides interlocking connections between the blocks to restrain the same from relative lateral shifting when viewed according to Figure 2. Thus the blocks 20 may be of relatively thin proportions so as to permit a double-walled structure with an air space therebetween in a wall of relatively limited thickness.

With the blocks assembled according to Figure 1, all rods are arranged in abutting relation

throughout the full height of the wall structure so as to effectively support the load effective on the wall. At the same time, the bars are encased in the blocks so as to be restrained from buckling.

Figure 7 illustrates the manner in which the blocks 20 in each of the wall shells 80 and 82 are arranged in reversed relation to provide overlapping joints. Both blocks 20 of Figures 6 and 7 are identical in construction. Each block includes two flanges 86 having angular faces 88 arranged to fit against the same angular faces of the adjacent blocks. Figure 13 illustrates the manner in which the flanges 86 are arranged in overlapping relation when assembled in the wall structure.

Figures 10, 11 and 12 illustrate one of the eave plates which cap the upper end of the wall structure made up of the shells 80 and 82 as illustrated in Figure 2. Referring to Figure 10, the eave plate 90 comprises sheet metal bent to provide troughs 92 spaced to align with the ribs 94 on the upper ends of the blocks 20 in the upper courses 18 of the two shells 80 and 82. The plates of the trough 92 are provided with openings 96 to provide anchorage for bolts which may be employed in securing angle plates and the like for mounting joist and rafters (not shown).

Ends of bars 72 projecting above the shells 80 and 82 may be cut off to permit mounting of the plates 90. These plates are spaced across the joints of the blocks 20 and the upper courses 18. Each plate is provided with four bars 98 which are arranged to project into the bores 70 and to meet the ends of the bars 72 as illustrated in Figure 1. Bars 98 are provided with transverse openings in the upper ends for the reception of pins 100 which permits the bars to be shifted to secure location thereof so as to align with the bores 70.

Figure 10 illustrates the trough as being provided with four openings 102 for selective reception of the pins 100 spaced according to the spacing between the bores 70 and the bars 72, so as to permit the bars 98 to be adjusted to the available bores 70.

In Figures 13, I illustrate the manner in which the wall structure is built to provide a corner. Blocks 20 in the positions 104 and 106 are of the same proportions as the block 20 illustrated in Figures 6 and 7. The corner block 108 is built in the inner shell 82, while the corner block 110 is built into the outer shell 80. The corner blocks are of the same height as the blocks 16 and 20.

In some cases it may be desirable or necessary to employ blocks in the shells 80 and 82 of shorter length than the regulation blocks 20. Figure 13 illustrates three-quarter length blocks of this type at 112. A half length block is illustrated at 114. In any event, the half or three-quarter length blocks are provided with bars and bores for keying connection in the same manner as the regulation blocks 20. The rod and bores are spaced according to the spacing of the blocks 20 so that the units are interchangeable, and the bore or bores in one block will always align with the bars in other blocks.

Figure 13 also illustrates two blocks 114 and 116 as having right-angular faces 118, which faces may define wall and door openings. Block 12 in the 122 position of Figure 13 may be of three-quarter length to define the outside corner of the building.

Figure 3 illustrates the manner in which the angular faces 88 in each course 18 are reversed with respect to the same angular faces in the

next higher or lower course. Thus it will be seen that the rib and groove keys at the bottom and top ends of the blocks in combination with the reverse overlapping of the flanges 86 provide an arrangement in which the joints are staggered and effectively keyed. All the bars projected into bores in adjacent building units fit snugly in those bores so as to provide effective keying of the wall structure.

10 In Figures 1 and 2 I illustrate one of a number of brackets 128 provided with a flange 130 which overlies the ledge 132 and is anchored to foundation blocks 14 by bolts 134. In Figure 1, the bracket 128 includes a U-shaped formation 136 for the reception of the floor joist 138. The floor of the building is indicated generally at 140. Figure 8 illustrates one of the blocks 20 as being provided with a transverse opening 142 and a slot 144.

15 Figure 2 illustrates the slot 144 as being located just underneath the floor 140 with the opening 142 located immediately above the floor. The slot and the opening may be aligned by a suitable metallic liner 146. In any event, the slot 144 and the opening 142 establish communication between the room underneath the floor and the one above.

20 Figure 9 illustrates one of the blocks 20 as being provided with one opening 148. This block is arranged in the outer shell 80 or inner shell 82 of Figure 1 in the upper course 18. This type of block may be employed for interior or exterior ventilating purposes, but does not necessarily constitute one of the essential blocks in the general wall structure of Figure 1.

I claim:

1. In a building structure, a plurality of precast blocks adapted to be arranged in superimposed courses to provide a wall, said blocks being provided with precast vertical openings, and a plurality of rods extending vertically through the blocks and beyond the top and bottom ends thereof distances equal to half the height of their respective blocks, said rods being precast in said blocks, the rods of the blocks in one course being receivable in the openings in the blocks in the adjacent course below and the adjacent course thereabove, said rods in the assembled relation of the blocks being arranged in end-to-end abutting relation throughout the full height of the wall and fitting snugly in said openings.

2. In a building structure, a plurality of precast blocks adapted to be arranged in superimposed courses to provide a wall, said blocks being provided with precast vertical openings, a plurality of rods extending vertically through the blocks and precast therein and extending beyond the top and bottom ends thereof distances equal to half the height of their respective blocks, the rods of the blocks in one course being receivable in the openings in the blocks in the adjacent course below and the adjacent course thereabove, said rods in the assembled relation of the blocks being arranged in end-to-end abutting relation throughout the full height of the wall and fitting snugly in said openings, a course of precast foundation blocks underneath the lowermost course of said first blocks, said foundation blocks being provided with precast bores for snugly receiving the rods projecting downwardly from the blocks in said lowermost course, and rods precast in the foundation blocks snugly receivable within the openings in the blocks in said lowermost course for engagement with the rods therein.

3. In a building structure, a plurality of pre-

cast blocks adapted to be arranged in superimposed courses to provide a wall, said blocks being provided with precast vertical openings, a plurality of rods extending vertically through the blocks and precast therein and extending beyond the top and bottom ends thereof distances equal to half the height of their respective blocks, the rods of the blocks in one course being snugly receivable in the openings in the blocks in the adjacent course below and the adjacent course thereabove, said rods in the assembled relation of the blocks being arranged in end-to-end abutting relation throughout the full height of the wall, a course of precast foundation blocks having precast bores and rods corresponding to the openings and rods of the said first blocks, and a second course of precast foundation blocks lying underneath said first-mentioned course of foundation blocks, said second course of foundation blocks being provided with precast bores for snugly receiving the rods projecting beyond the lower ends of the foundation blocks in said first-mentioned course and precast rods snugly receivable within the bores in the foundation blocks in the first course, said rods in the assembly of all said blocks being arranged in end-to-end relation throughout the full height of the wall structure.

4. In a building structure, a plurality of precast blocks adapted to be arranged in superimposed courses to provide a wall, said block being provided with precast vertical openings, a plurality of rods extending vertically through the blocks and precast therein and extending beyond the top and bottom ends thereof distances equal to half the height of their respective blocks, the rods of the blocks in one course being snugly receivable in the openings in the blocks in the adjacent course below and the adjacent course thereabove, said rods in the assembled relation of the blocks being arranged in end-to-end abutting relation throughout the full height of the wall, and eave plates mounted on the top of the top course having rods attached thereto for insertion in the openings in the blocks in the top course.

5. In a building structure, a plurality of precast blocks adapted to be arranged in superimposed courses to provide a wall, said block being provided with precast vertical openings, and a plurality of rods extending vertically through the blocks and precast therein and extending beyond the top and bottom ends thereof distances equal to half the height of their respective blocks, the rods of the blocks in one course being snugly receivable in the openings in the blocks in the adjacent course below and the adjacent course thereabove, said rods in the assembled relation of the blocks being arranged in end-to-end abutting relation throughout the full height of the wall, said blocks having overlapping flanges.

6. In a building structure, a plurality of precast blocks adapted to be arranged in superimposed courses to provide a wall, said block being provided with precast vertical openings, a plurality of rods extending vertically through the blocks and precast therein and extending beyond the top and bottom ends thereof distances equal to half the height of their respective blocks, the rods of the blocks in one course being snugly receivable in the openings in the blocks in the adjacent course below and the adjacent course thereabove, said rods in the assembled relation of the blocks being arranged in end-to-end abut-

- ting relation throughout the full height of the wall, and means cooperable between the blocks in one course and the adjacent course to restrain the courses from lateral displacement.
5. In a building structure, a plurality of precast blocks adapted to be arranged in superimposed courses to provide a wall, said block being provided with precast vertical openings, and a plurality of rods extending vertically through the blocks and precast therein and extending beyond the top and bottom ends thereof distances equal to half the height of their respective blocks, the rods of the blocks in one course being snugly receivable in the openings in the blocks in the adjacent course below and the adjacent course thereabove, said rods in the assembled relation of the blocks being arranged in end-to-end abutting relation throughout the full height of the wall, said blocks being provided with cooperating means for restraining the blocks from lateral displacement.
8. In a building structure, a plurality of precast blocks adapted to be arranged in superimposed courses to provide a wall, said block being provided with precast vertical openings, and a plurality of rods extending vertically through the blocks and precast therein and extending beyond the top and bottom ends thereof distances equal to half the height of their respective blocks, the rods of the blocks in one course being snugly receivable in the openings in the blocks in the adjacent course below and the adjacent course thereabove, said rods in the assembled relation of the blocks being arranged in end-to-end abutting relation throughout the full height of the wall, said blocks being assembled to provide two wall shells arranged in spaced relation.

ANGLE W. POWELL. 20
